UNITED STATES PATENT OFFICE.

JOHN ALBERT FERGUSON, OF DENVER, COLORADO.

WALL CONSTRUCTION.

SPECIFICATION forming part of Letters Patent No. 767,398, dated August 16, 1904.

Application filed February 23, 1904. Serial No. 194,822. (No model.)

To all whom it may concern:

Be it known that I, JOHN ALBERT FERGUSON, a citizen of the United States of America, and a resident of Denver, in the county of Denver and State of Colorado, have invented 5 certain new and useful Improvements in Wall Construction, of which the following is a specification.

This invention relates to certain new and 10 useful improvements in wall construction, having for its objects, among others, to provide a wall possessing maximum strength, durability, and compactness, combined with heat, cold, and moisture resisting properties, air-spaces being provided which may be utilized 15 for water, gas, or soil pipes, or for electric wiring or other purposes.

I construct the wall either straight or curved 20 of blocks of concrete or other suitable material and comprising a body portion with an arm or arms or projections extending at an angle therefrom upon one side laid in the wall and bonded by the arms or projections of the one block alternating with and over-lapping those of the next block and provided 25 upon their opposed faces with grooves into which a wire, rod, bar, or other tying member is seated, thus tying the blocks and wall together.

30 In some instances the tie wire or rod may be provided with a rod or arm extending at an angle therefrom inward and adapted to be secured to a joist, beam, or girder. The wall may be built up of a plurality of blocks in depth, so as to form a plurality of air-spaces in depth, in which case as many tie-rods are employed in each horizontal row of blocks as there are air-spaces in depth in the wall.

Other objects and advantages of the invention 40 will hereinafter appear, and the novel features thereof will be specifically defined by the appended claims.

The invention in some of its embodiments is clearly illustrated in the accompanying 45 drawings, which, with the numerals of reference marked thereon, form a part of this specification, and in which—

Figure 1 is a perspective view with a portion broken out showing one mechanical form 50 embodying the invention, the tie-rod on the

upper course being omitted. Fig. 2 is an enlarged detail of a portion of the wall shown in Fig. 1. Fig. 3 is a top plan showing another form of embodiment of the invention. Fig. 4 is a top plan of still another form, the view being taken as upon the line 4-4 of Fig. 5 looking down. Fig. 5 is a vertical section from front to rear of the wall as upon the line 5-5 of Fig. 4.

Like numerals of reference indicate like parts in the different views.

I desire to here state that the construction hereinafter described and claimed is capable of embodiment in any style of wall, either straight or circular or other shape, and for any and all purposes, either that of a building, a tank or well, elevator-shafts, grain-elevators, bridge construction, dams, or any and all uses in which it may be desired or advisable to employ a wall of this nature. The forms herein illustrated are given merely as examples, and the invention is in no wise restricted to the particular form of wall herein shown. With this understanding, then, the principle of the invention will now be described.

Referring first to Figs. 1 and 2, 1 designates the blocks, which in this form each comprise a body portion 2, from which extend upon one side the substantially central arm or projection 3 and at each end upon the same side of the body portion the shorter arms or projections 4. These arms or projections may be of any desired length, depending upon the nature of the wall to be constructed. Each of the long arms or projections 3 is provided upon each of its top and bottom faces with a groove 5, the shape of which will depend upon the shape of the tie rod or bar employed. In the present instance the tie rod or bar is shown as of circular or cylindrical form, and hence the grooves are each substantially semicircular in form. With other forms of tie bar or rod the grooves will be of a shape conforming thereto. In building the wall blocks of this character are laid side by side in courses. In Figs. 1 and 2 there are two such blocks in thickness in each course. The one block is laid with its long arm or projection 3 extended inward and the next block with its long arm extended outward, as will be readily un-

derstood from Fig. 2. In this way the long arms of the one block overlap and alternate with those of the next block, and when the mortar 6 is laid upon the upper faces of the blocks the same are bonded in the wall by reason of this alternately oppositely disposed arrangement of the arms or projections, and when the tie rod or bar 7 is laid upon top of each course and fitted in the opposed grooves 10 of the adjacent faces of the blocks the arms or projections are so held and the entire wall of blocks so bonded that it is made practically as one homogeneous mass. As will be readily understood from Figs. 1 and 2, the blocks in each two adjacent courses are so disposed as to break joints, the long arms of the blocks in the lower course being disposed between the long arms of the blocks in the next course. This may be accomplished by simply moving the blocks of the next course to the right or left one-half length of a block. This tends to further bond the blocks and wall, as will be readily understood.

In Fig. 3 I have shown how the wall may be built up of a different form of block and produce practically the same wall. In this view the blocks 8 each have an arm or projection 9 at each end, and these blocks are disposed and laid in the wall in the manner clearly illustrated in said Fig. 3. The blocks are laid alternately, reversely in position—that is, the one is laid with its arms projecting inward and the next with its arms projecting outward—the adjacent arms of the two adjacent blocks being parallel with each other and in close proximity to each other, as seen clearly in Fig. 3. The upper faces of the arms or projections are provided with grooves into which the tie rod or bar 10 is seated in the same manner as the tie rod or bar above described with reference to Figs. 1 and 2, the bonding effect being thus retained.

In Fig. 3 I have shown how the tie rod or bar may be provided with an arm or arms 11, extending inward therefrom and affixed thereto in any suitable manner, as by being twisted thereabout, as seen in said view. This arm or these arms are designed to be secured to a joist, beam, girder, or other timber for further tying or bonding the wall thereto. The mode of attachment of these arms to the tie rod or bar, as above mentioned, is advantageous in that it allows of adjustment along the said rod or bar to bring the arm to the desired point for proper attachment to its joist or other member; but it is to be distinctly understood that no restriction is made in this regard and that these arms may be affixed to or project from the tie rod or bar in any convenient or preferred manner.

In Figs. 4 and 5 I have shown still another form of embodiment of the invention. In these views I have shown how the thickness of the wall may be increased and more than one air-space in the depth of the wall pro-

vided. In this form of wall I employ blocks 12, each having but one arm or projection and that extending from substantially the length of the block. These arms or projections are provided with grooves 14, similar to the grooves in the form shown in Figs. 1 and 2 and for a similar purpose. These blocks are so laid in the wall that their arms extend alternately in opposite directions overlapping at the mid-length of the distance between two blocks and the long arm of the one block comes opposite the meeting edges of blocks in the next row. In this form of invention there are employed two tie rod bars 15 and 16, as seen, and the arrangement is such that the blocks are so bonded and into the wall that it is made practically a homogeneous mass. In this form, Fig. 4, the wall upon one side, which may be either inner or outer, is of double thickness, as seen at 17. The blocks in the different courses may be so laid that the two tie rods or bars will lie in different horizontal planes, as seen in Fig. 5. This gives a still better bond effect.

It is to be noted that the air-spaces 18 in Figs. 1 and 2 and the double air-spaces 19 and 20 in Figs. 4 and 5 are formed by the spacing of the blocks by their arms or projections so that the blocks themselves are not formed so as to fill the spaces with air-spaces extending therethrough. The wall with the plurality of air-spaces in depth, as seen in Figs. 4 and 5, gives increased protection against heat, cold, or moisture, and it is evident that if it be desired to construct a wall of greater thickness the same may readily be done and a correspondingly great number of air-spaces in depth provided by employing either form of blocks herein illustrated or others and so disposing them as to provide the required thickness of wall and number of air-spaces in depth.

The above is believed to be sufficient to clearly explain the principle herein involved and while the structural embodiment of the invention as herein disclosed is what I at the present time consider preferable it is evident that the same is subject to changes, variations and modifications without departing from the spirit of the invention or sacrificing any of its advantages. I therefore do not wish to be restricted to the details hereinbefore described nor as shown in the drawings, but reserve the right to make such changes, variations and modifications as come properly within the scope of the protection prayed.

What is claimed as new is—

1. A wall composed of a plurality of blocks, each having a projection and the projection disposed to extend in opposite directions and means in addition to the mortar joining the overlapped projections to form bonds.

2. A wall composed of blocks, each having a projection and the blocks laid in the wall with the projections alternately oppositely

disposed, and a tie-rod engaging said arms and tying the same in the wall.

3. A wall composed of a plurality of blocks each having a projection, the blocks being laid in the wall with the projections alternately oppositely disposed and overlapping, and grooved upon their adjacent faces, and a tie-rod seated in said grooves and bonding the projections and blocks in the wall.

10 4. A wall composed of a plurality of blocks with arms, the arms being arranged to form bonds, the blocks being laid in the wall to form air-spaces multiple in depth, and continuous means tying the said arms in the wall.

15 5. A wall composed of a plurality of blocks, each with an arm, the blocks being laid in the wall with a plurality in depth to form a plurality of air-spaces in depth, and tie-rods engaging the overlapped arms to tie the same in the wall.

20 6. A wall composed of blocks, each block having an arm projecting at an angle thereto, the blocks being laid in the wall with their arms overlapping, and forming air-spaces of a plurality in depth, the blocks in adjacent courses being laid with their arms in different

vertical planes, and continuous tie-rods engaging said arms to bond them.

7. A wall composed of blocks each having an arm projecting at an angle therefrom, said blocks being laid in the wall with their arms alternately oppositely disposed and overlapping, the arms in adjacent courses being disposed in different planes, and tie-rods engaging grooves in said arms and disposed in different planes.

30 8. A wall composed of blocks having overlapping arms, and a tie-rod engaging said arms to bind them together, and lateral arms on said tie-rod for attachment to a support.

40 9. A wall composed of blocks having overlapping arms disposed in alternate opposite directions, a tie-rod engaging said arms, and lateral arms adjustably mounted on said tie-rod.

45 Signed by me at Washington, District of Columbia, this 22d day of February, 1904.

JOHN ALBERT FERGUSON.
